J. VIDETTA

GARBAGE CAN RECEPTACLE

Filed July 9, 1925

Patented Apr. 27, 1926.

1,582,807

UNITED STATES PATENT OFFICE.

JOHN VIDETTA, OF WEEHAWKEN, NEW JERSEY.

GARBAGE-CAN RECEPTACLE.

Application filed July 9, 1925. Serial No. 42,505.

To all whom it may concern:

Be it known that I, JOHN VIDETTA, a subject of the King of Italy, residing at Weehawken, in the county of Hudson and State 5 of New Jersey, have invented certain new and useful Improvements in Garbage-Can Receptacles, of which the following is a specification.

This invention relates to new and useful 10 improvements in garbage can receptacles.

The primary object of this invention is to provide a receptacle which may be employed for housing garbage cans, and the like, for providing a more sanitary place for storing 15 garbage and other refuse.

A further object of the invention is to provide an improved form of closure operator for the above type of receptacle.

Other objects and advantages of the invention will be apparent during the course 20 of the following description.

In the accompanying drawing forming a part of this specification and in which like numerals are employed to designate like 25 parts throughout the same,

Figure 1 is a side elevational view, partly broken away, of the receptacle embodying this invention,

Figure 2 is a top plan view of the structure shown in Fig. 1,

Figure 3 is a fragmentary vertical sectional view taken upon lines III—III of Fig. 2,

Figure 4 is a horizontal sectional view 35 taken upon line IV—IV of Fig. 1,

Figure 5 is a fragmentary vertical sectional view taken upon lines V—V of Fig. 2,

Figure 6 is a detail perspective view of a 40 portion of the receptacle closure and illustrates in detail means for guiding and holding the cover against lateral shifting movement when arranged in its closed position, and

Figure 7 is a similar view to Fig. 6, but shows a point arranged diametrically opposed thereto and illustrates in detail the connection between the cover and its operating or opening means.

In the drawing, wherein for the purpose 50 of illustration is shown a preferred embodiment of this invention, the numeral 5 designates the body portion of the receptacle which is of cylindrical shape and has a bottom wall 6 formed thereon. Extending longitudinally of the body portion 5 and ar-

ranged on diametrically opposite sides thereof are the two uprights or guides 7 which are connected at their lower and upper ends to the lower and upper reinforcing flanges 60 8 and 9 respectively.

A cover consisting of the hingedly connected sections 10 and 11 is provided for closing the upper end of the body portion 5 and is formed with the brace members 12 65 which are rigidly connected to the lower face of the cover section 11 and underlie the lower face of the cover section 10 to prevent the section 10 from pivoting downwardly in respect to the section 11. The 70 intermediate portion of the periphery of the cover section 11 is provided with a notch 13 into which projects the end 14 of a depending, cover opening rod 15 which extends longitudinally, downwardly of the 75 body portion 5 of the receptacle and is connected at spaced points to the receptacle encircling rings 16 and 17. The upper end 14 of the rod 15 is pivotally connected to the cover sections 11 by the pivot pin 14^a 80 as shown more clearly in Figs. 5 and 7. Extending longitudinally of the receptacle and arranged at a point diametrically opposite to the rod 15 is a second rod 18 which is connected to the aforementioned rings 16 85 and 17 and has its upper end bifurcated at 19, see Figs. 2 and 6, so that its furcations may enter the spaced apertures 20 formed in the cover section 10 adjacent its periphery. The entrance of these furcations 19 into the apertures 20 is intended to prevent the cover from unintentionally being shifted laterally when in its closed position and thereby preventing the upper end of the receptacle body 5 from being partially opened 90 or uncovered.

It will be seen, by inspecting Figs. 2 and 5, that the cover section 11 will rest upon the upper flange 9 of the body portion 5 and that the operating rod 15 is connected thereto outwardly of the fulcrum line provided by this cutaway edge 5^a of this flange. In view of this fact, any pressure applied to the rings 16 and 17 which will cause the same to move downwardly along the receptacle body 5, will cause the cover to be swung upwardly, pivoting upon the fulcrum edge 5^a, to open the upper end of the body portion 5. It will be noted, by inspecting Figs. 1 and 4, that the rings 16 and 17 are provided with notches 21 which receive the guides 7 for the purpose of insuring the proper lon-

100

105

110

gitudinal movement of the rings 16 and 17 when pressure is applied thereto.

For the purpose of returning the cover to its closed position after pressure is removed 5 from the rings 16 and 17, a spring 22 is connected at its upper end to the cover section 11 and extends downwardly through the bore of a substantially cylindrical cage 23, which is fastened to the inner face of the 10 side wall of the body portion 5, and has its lower end connected to a pin 24 which intersects the lower end portion of the bore of the cylindrical cage 23.

It is to be understood that the form of this 15 invention herewith shown and described is to be taken as a preferred example of the same, and that various changes in the shape, size, and arrangement of parts may be resorted to without departing from the spirit 20 of the invention or the scope of the subjoined claims.

Having thus described the invention, I claim:—

1. In a receptacle of the type described, a 25 body portion open at its upper end, a cover for closing said upper end, formed of a pair of hinged sections, a rod connected to one of the cover sections outwardly of the upper edge of the body portion, and a ring slidably 30 encircling the body portion and connected to the rod whereby downward pressure applied to the ring will cause both cover sections to swing into an open position and with the other cover section capable of being normally opened without operating the ring.

2. In a receptacle of the type described, a 35 body portion open at its upper end, a cover for closing said upper end, formed of a pair of hinged sections, a rod connected to one of the cover sections outwardly of the upper edge of the body portion, a ring slidably encircling the body portion and connected to the rod whereby downward pressure applied to the ring will cause both cover sections to 40 swing into an open position, and with the other cover section capable of being normally opened without operating the ring, and a spring for returning the cover sections to their closed position.

50 3. In a receptacle of the type described, a body portion open at its upper end, a cover for closing said upper end, a rod connected

to the cover outwardly of the upper edge of the body portion, a ring slidably encircling the body portion and connected to the rod whereby downward pressure applied to the ring will cause the cover to swing into an open position, and a second rod connected to the movable ring and extending perpendicularly therefrom to engage the cover 55 when in a closed position for preventing the latter from working laterally into a position to uncover a portion of the upper end of the body of a receptacle.

4. In a receptacle of the type described, a 60 body portion open at its upper end, a cover for closing said upper end, a rod connected to the cover outwardly of the upper edge of the body portion, a ring slidably encircling the body portion and connected to the rod 65 whereby downward pressure applied to the ring will cause the cover to swing into an open position, a second rod connected to the movable ring and extending perpendicularly therefrom to engage the cover when in a 70 closed position for preventing the latter from working laterally into a position to uncover a portion of the upper end of the body of the receptacle, a substantially cylindrical cage carried by the wall of the body 75 portion and within the latter, and a spring located within the cage and connected at its lower end to the cage and at its upper end to the cover for returning the latter to its closed position.

5. In a receptacle of the type described, a 80 body portion open at its upper end, a cover for closing said upper end, a rod connected to the cover outwardly of the upper edge of the body portion, a ring slidably encircling the body portion and connected to the rod 85 whereby downward pressure applied to the ring will cause the cover to swing into an open position, a second rod connected to the movable ring and extending perpendicularly therefrom to engage the cover when in a closed position for preventing the latter from working laterally into a position to uncover a portion of the upper end of the body 90 of the receptacle, and guiding members for 95 said ring connected to the body portion.

In testimony whereof I affix my signature.

JOHN VIDETTA.
